UNITED STATES PATENT OFFICE.

OTTO HOFFMANN, OF WITTINGTON, ENGLAND.

AUTOMATIC FIRE-EXTINGUISHER.

SPECIFICATION forming part of Letters Patent No. 634,457, dated October 10, 1899.

Application filed May 10, 1898. Serial No. 680,312. (No model.)

To all whom it may concern:

Be it known that I, OTTO HOFFMANN, engineer, a subject of the Emperor of Germany, residing at 18 Wellington road, Withington, 5 near Manchester, in the county of Lancaster, England, have invented certain new and useful Improvements in or Connected with Automatic Fire-Extinguishers, of which the following is a specification.

10 My said invention relates to improvements in or connected with automatic fire-extinguishers of the "sprinkler" type; and it consists, mainly, of a system of levers to maintain the valve of the spindle upon its seat, 15 which levers serve also to effect a rapid opening of the valve when required.

In order that my invention may be properly understood, I will describe the same with reference to the accompanying sheet of drawings.

In the said drawings, Figure 1 represents in outside elevation a sprinkler constructed in accordance with my invention. Fig. 2 is a view of the arrangement of levers at right angles to Fig. 1. Fig. 3 is a sectional elevation of the sprinkler, showing more clearly the arrangement of levers. Fig. 4 is an outside elevation of the sprinkler at right angles to Fig. 3 after the disruption of the levers, 25 and the fall of the valve. Fig. 5 is a diagrammatic view of the arrangement of levers, showing the points where power is exerted.

In carrying my invention into effect I form the sprinkler-head with a valve-seating to 35 accommodate a valve *a*, preferably made of aluminium. To support the valve *a* upon its seating in the sprinkler-head, I provide an inclined lever *b*, the lower end of which is formed with a projection *b'*, which sits loosely within 40 a recess *c*, formed in the end of an adjusting-screw *d*. This regulating-screw *d* passes through the center of the usual disperser-diaphragm *e*. Instead of an adjustable screw a fixed projection may be employed, if desired.

45 At about the center of the lever *b* I form a notch or support *b²*, upon which rests a short lever *f*, which is inclined in a contrary direction to the lever *b*. The lower end of the lever *f* rests upon the notch or support *b²* of 50 the lever *b*, the upper end being formed with a projection *f'*, engaging with a recess *a'* of the valve *a*.

Within the sprinkler-head is screwed a ring *g*, formed with an annular groove or recess *g'*, within which I place the hooked end of a long 55 lever *h*. The lower end of the lever *b* is provided with a bolt *i*, and the upper end of this lever bears against the hooked lever *h*, as will be clearly seen from an inspection of the drawings. The bolt *i* is arranged to be passed 60 through a slit *h'*, formed at the lower end of the lever *h*. By pressing the lower end of the lever *h* inward, the lever *h* bearing upon the upper end of the lever *b*, the two short angularly-disposed levers *b f* are also pressed inward with 65 an elastic pressure, thus securely holding the valve *a* upon its seat. The pressure may be increased by screwing up the regulating-screw *d*, which will have the tendency to increase the angle of levers *b* and *f*. The bolt *i*, having been 70 passed through the slit *h'* of the lever *h*, is secured by means of the wedge *j*, fusible metal being employed to maintain the wedge in position. The disperser-diaphragm *e* is connected to the head of the sprinkler by arms *k*, one 75 of these arms *k* being shown broken away in Fig. 1 to more clearly show the arrangement of levers.

From an inspection of the diagram Fig. 5 it will be noted that on pressing the lower 80 end of the long lever *h* inward in the direction of the arrow the pressure is communicated to the top of the lever *h* at the point where the broken end bears in the annular recess in the direction of the arrow 1, and the pressure is 85 communicated to the top of the lever *b*, exerting a force in the direction of the arrow 2. The force is then communicated to the center of the lever *b* at the point and in the direction of the arrow 3 and also in an upward and downward direction, as shown by the arrows 4 and 5. As the pressure thus applied to the hooked lever *h* thrusts the levers *b f* in a direction tending to make them assume a straight line, the leverage exerted is not only very great, but 90 also an elastic pressure is brought to bear upon them. When, therefore, the fusible metal is melted by the increase of temperature caused by a fire, the wedge *j* is at once ejected from the bolt *i*, the hooked lever *h* springs outward, 95 and the angular valve-supporting levers *b f* at once collapse and the valve is opened by the water-pressure, as shown in Fig. 4. The sprinkler-head may be placed either above or

below the water-pipe, as the elastic pressure exerted by the hooked lever *h* is fully adequate to effect the complete disruption of the levers in any position in which the sprinkler-head 5 may be placed.

I do not confine myself to the exact method of securing the levers by the fusible metal, as described, as this may be varied. The method shown, however, has distinct advantages. For 10 instance, it is found in practice that on continued exposure to the atmosphere fusible metal becomes oxidized and softened, thus rendering the sprinkler liable to be brought into action when not required simply by being 15 unable to withstand any pressure which may be exerted upon it. By employing a wedge held in position by the fusible metal the fusible metal entering the bolt on each side of the wedge is protected to a very large extent 20 and shielded from atmospheric contact. In case, therefore, any excess of the fusible metal outside the bolt should be affected by atmospheric influences the fusible metal in the bolt being protected as described is unaffected 25 thereby and is sufficient to retain the wedge in position until melted by a dangerous increase of temperature.

The bolt *i* and wedge *j* are by preference made of copper or other metal rapidly conducting heat.

I claim—

1. In a sprinkler the combination with the valve-seat and the support for the strut, of the valve, a strut member *b* having one end seated on said support and having a shoulder

and an outwardly-extending upper end, a second strut member *f* extending between said shoulder and the valve, said strut members being angularly arranged with relation to each other, an annular groove in the sprinkler-head, a bar or lever having its upper end seated in said groove and a pin fusibly connecting the lower end of the bar with the lower portion of the strut member *b*, the intermediate portion of said bar *h* having a free 40 bearing against the outwardly-extending end of the strut member *b*, substantially as described.

2. In combination, the sprinkler-head, a ring *g* threaded therein having an inner annular groove or channel, a valve-seat on said head, a support for the strut, a strut member *b* having one end seated on said support and having an outwardly-bent upper portion and a shoulder, a second strut member *f* extending between said shoulder and the valve, a bar *h* having a lateral extension in its upper end detachably engaging said groove and a pin fusibly connecting the lower end of said bar *h* with the lower portion of the strut member *b*, the intermediate portion of the bar *h* bearing freely against the outwardly-extending end of the strut member *b*, substantially as described.

In witness whereof I have hereunto set my 65 hand in presence of two witnesses.

OTTO HOFFMANN.
